SPIKE PULLER

Paul G. Nichols and James D. Nichols,
Riverton, Ky.

Application April 20, 1937, Serial No. 138,048

4 Claims. (Cl. 254—21)

This invention appertains to new and useful improvements in means for pulling spikes from railway ties and other structures without causing distortion of the spike head. There is in use at present a spike having an arched head structure with which the present invention is especially adapted for use, this particular spike structure forming the basis of Patent No. 2,015,194 issued September 24, 1935.

The principal object of the present invention is to provide a simple device which can be readily fastened to the head of a spike so that a claw bar can be used in conjunction therewith without resulting in such malformation of the spike head as to prohibit its further use.

Other important objects and advantages of the invention will become apparent to the reader of the following specification.

In the drawing:—

Figure 1 represents a vertical sectional view fragmentarily showing a tie and rail and the puller in side elevation.

Figure 2 is a fragmentary top plan view.

Figure 3 is an end elevational view.

Figure 4 is a plan view of the key.

Figure 5 is a vertical sectional view taken substantially on the line 5—5 of Figure 1.

Referring to the drawing wherein like numerals designate like parts, it can be seen that numeral 5 represents the standard railway tie upon which the usual plates 6 are placed for supporting the rails 7.

The plate 6 is provided with spike openings therein which are registerable with bores 8 formed in the tie for the reception of the spike shank 9. Numeral 10 generally refers to the spike which as shown is of special design such as is clearly represented in Patent No. 2,015,194, issued September 24, 1935. This type of spike is formed by bending an elongated rod of square cross section back upon itself and then bending the free end portions laterally to form an arch-shaped head formation. This head formation is denoted by numeral 11 and its free end portion bears upon the rail base shown in Figure 1 when the spike is completely driven into the tie 5.

Thus it can be seen that with this form of spike the puller generally referred to by numeral 12 can be readily and efficiently used.

The puller 12 consists of an arch-shaped portion 13 curved in the opposite direction from the rocker runners 14—14. This arched portion 13 and the runners or rockers 14—14 are constructed in one piece and this body has one end curved downwardly as at 15 and its opposite end like-

wise curved downwardly and provided with a notchway 16 for the reception of the free end of the spike head.

The key generally referred to by numeral 17 consists of the key head 17 and the slotted arm 18, the key head 17 and arm 18 being in parallel relation and connected by the shank 19.

A machine screw or the like 20 is disposed through the slotted arm 18 and into the end portion 15 of the puller 12 so that the key head 17 can be slid inwardly or outwardly with respect to the puller.

When it is desired to apply the puller, the device is set upon the spike so that the arched portion 13 rests upon the arched spike head while 15 the runners 14—14 depend at opposite sides of the spike head. The key 17 is now slid inwardly under the arch 13 and also under the head 11 of the spike 10 thus latching the device to the spike head. The puller is now in position to be 20 rocked.

A claw bar 21 can now be used by placing its head under the portion 15 of the puller and gradually lifting up on the puller as the claw 25 is inserted. Thus the puller is rocked and in so being rocked gradually pulls the spike from the tie.

While the foregoing specification sets forth the invention in specific terms, it is to be understood that numerous changes in the shape, size 30 and materials may be resorted to without departing from the spirit and scope of the invention as claimed hereinafter.

Having described the invention what is claimed as new is:—

1. A puller for pulling spikes of the arched head type comprising a plate having one end portion formed to facilitate the engagement thereunder of a prying tool, an arch-shaped formation on the plate for engagement over the top of a spike head, and a member on the plate shiftable for disposition under the head portion of a spike.

2. A puller for pulling spikes of the arched head type comprising a plate having one end portion formed to facilitate the engagement thereunder of a prying tool, an arch-shaped formation on the plate for engagement over the top of a spike head, and a member on the plate shiftable for disposition under the head portion 45 of a spike, said shiftable member consisting of a pin and a slidale connection between the pin and the plate.

3. A puller for pulling spikes of the arched head type comprising a plate having one end 50

- portion formed to facilitate the engagement thereunder of a prying tool, an arch-shaped formation on the plate for engagement over the top of a spike head, and a member on the plate 5
5 shiftable for disposition under the head portion of a spike, said shiftable member consisting of a pin and a shiftable connection between the pin and the plate, said slidable connection consisting of an arm on the pin having an opening 10 therein and a securing element disposed through the opening and into the plate.

4. A puller for pulling spikes of the arched

head type comprising a plate having one end portion formed to facilitate the engagement thereunder of a prying tool, an arch-shaped formation on the plate for engagement over the top of a spike head, and a member on the plate 5 shiftable for disposition under the head portion of a spike, said plate being in the form of a rocker and adapted to rock when moved by a prying tool.
